(57) **CLAIM**

The ornamental design for an herb storage container lid as shown and described.

DESCRIPTION

FIG. 1 shows a perspective view of the herb storage container lid in accordance with the present invention;

FIG. 2 shows a front view of the herb storage container lid of FIG. 1;

FIG. 3 shows a rear view of the herb storage container lid of FIG. 1;

FIG. 4 shows a right-side view of the herb storage container lid of FIG. 1;

FIG. 5 shows a left-side view of the herb storage container lid of FIG. 1;

FIG. 6 shows a top view of the herb storage container lid of FIG. 1;

(Continued)

FIG. 7 shows a bottom view of the herb storage container lid of FIG. 1; and,
 FIG. 8 shows a cross-sectional view taken through line 8-8 of the herb storage container lid of FIG. 1.
